UNITED STATES PATENT OFFICE

CARL ALFRED JOHANSSON, OF BAEKKELAGSHOGDA, NEAR OSLO, NORWAY

PULLEY BLOCK

Application filed May 28, 1929, Serial No. 366,740, and in Great Britain September 28, 1928.

The invention relates to a pulley block particularly suitable for use as a self-acting life-saving apparatus in the event of fire. It is constructed so that a load applied to either 5 of the two ends of the lowering line will be automatically lowered at a limited speed and as soon as one load is removed from one end of the line the apparatus is ready for lowering another load on the other end of the line 10 which has been lifted during the lowering of the first load.

Such pulley blocks are known per se.

The speed-regulating mechanism in such known pulley blocks consists of a pendulum 15 coacting with a star wheel on the shaft in such a manner that the turning motion is dependent upon the oscillations of the pendulum. Theoretically the apparatus fulfills any requirement which may be made of such 20 a device. However the construction is rather complicated and consequently expensive. The apparatus must be made very accurate if it is to act in the desired manner; the rattling noise is unpleasant to the person lowering and after a rather short time of use the wearing may cause the regulating wheel to stick so that the lowering is interrupted.

The purpose of the invention is now to avoid these inconveniences.

According to this invention the pendulum is pivoted at its lower end and carries at its upper end the pulley and a starwheel integral therewith. The starwheel coacts with a rigid 25 guide the lower face of which is concentric with the pivot of the pendulum and the teeth of the starwheel are formed so that the surfaces of the same alternately take up a position along the guide face. In order that a turning motion of the starwheel may be possible the guide is provided with a recess in which the teeth may be turned when the starwheel is carried to the end of its oscillations.

The invention is illustrated in the accompanying drawings in which Fig. 1 shows in a sectional view a preferred form of the same.

Fig. 2 is a vertical sectional view of the same at right angles to Fig. 1.

Figs. 3 and 4 are diagrammatic vertical sectional views showing two different positions of the movable parts of the block.

The block consists of a frame having two side-parts 1 and an upper connecting part 2. The block is connected to a hook 3, by means of which the device may be fastened to a suitable support. In the frame 1, 2 is pivoted, by means of a pin 4, a pendulum 5. The upper edge 6 of the pendulum is curved concentrically with the pin 4 and slides along a rigid guide 7 which is also concentric with the pin 4. In the pendulum is supported, by means of a pin 8, a pulley 9 integral with a starwheel 10. The teeth of the starwheel contact with a rigid guide 11 having a lower guide face 12 concentric with the pin 4 and a recess 13. The teeth of the starwheel are, as appears from the drawing, formed in accordance with the face 12. The pendulum further is provided with two guide rolls 14, 15 for each part of the line 16. The contact of the line around the pulley 9 is secured by placing the same on the inner side of the upper rolls 14 and the outerside of the lower rolls 15.

The position shown in Figure 1 is not a fixed position, but only an intermediate position. If the right hand line part 16 is loaded, the parts will first take the position shown in Figure 3 wherein the right hand side of the star wheel tooth *t* located in recess 13 is in contact with the recess side. When the line 16 is pulled downwardly as indicated by the arrow with a sufficient force, the star wheel 10 tends to rotate clockwise, but because of the contact at *s* no simple rotation can take place. The contacting tooth *t* will press upon the guide formed by one side of the recess 13 and begin to slide at *s*. This can occur only by the tooth *t* pushing the whole wheel and pendulum back to the left (counter-clockwise) about the stationary pin 4. During this motion the tooth tip *t* is sliding at *s* gradually downwardly from the position shown in Figure 3 into the position shown in Figure 4 (the star wheel during such motion turning somewhat clockwise). When the tooth tip *t* has reached the position shown in Figure 4, it is about to leave the recess 13 and this occurs upon a further slight rotation of the star wheel. Thereby the tip *t* will be free of the recess and slip

under the guide 12. At the same time, the tooth t^3 will enter into contact with the guide 12 at the left hand side. The tooth t^2 is now within the recess and by the pull on the line 5 16 the whole pendulum will suddenly rock clockwise about the pin 4, so as to put the tooth t^2 in contact with the right hand side of recess 13, the parts resuming the position shown in Figure 3. Consequently the pendulum will rock to and fro (two strokes) 10 each time a new tooth enters recess 13, as will be understood.

When the load on the right part of the line has been lowered the left part may be loaded 15 and the right part lifted. The device will in this even act quite in the same manner as described above.

It will be understood that the details may be modified without departing from the scope 20 of the invention.

Having now particularly described and ascertained the nature of my said invention and in what manner the same is to be performed, I declare that what I claim is:—

25 1. In a pulley block, a rigid frame, a pendulum pivoted to the frame at its lower end, a pulley supported in the same, a starwheel integral with the pulley, means for guiding the starwheel and turning the same, and 30 means for keeping a line in contact with the pulley.

2. In a pulley block, a rigid frame, a pendulum pivoted to the frame at its lower end, a guide at its upper end concentric with the 35 pivot and coacting with a rigid guide, a pulley supported by the pendulum, a starwheel integral with the pulley, means for guiding the starwheel and turning the same and means for keeping a line in contact with the pulley.

40 3. In a pulley block, a rigid frame, a pendulum pivoted to the frame at its lower end, having a guide at its upper end concentric with the pivot and coacting with a rigid guide, a pulley supported by the pendulum, 45 a starwheel integral with the pulley, a further rigid guide concentric with the pivot of the pendulum, a recess in the latter guide, the teeth of the starwheel being curved in accordance with the latter guide, and means 50 for keeping a line in contact with the pulley.

4. In a pulley block, a rigid frame, a pendulum pivoted to the frame at its lower end, having a guide at its upper end concentric with a rigid 55 guide, a pulley supported by the pendulum, a starwheel integral with the pulley, a further rigid guide, concentric with the pivot of the pendulum, a recess in the latter guide, the teeth of the starwheel being curved in accordance 60 with the latter guide and a number of line guide rollers supported turnably in the pendulum and arranged so as to keep a line in contact with the pulley.

CARL ALFRED JOHANSSON.
